UNITED STATES PATENT OFFICE.

HIPPOLYTE NEVEU, OF PARIS, FRANCE, ASSIGNOR TO YSABEL DE PANIAGUA, OF PARIS,
FRANCE.

APPARATUS FOR THE SOLIDIFICATION OF LIQUID HYDROCARBONS.

Original application filed April 3, 1922, Serial No. 549,141, and in France January 27, 1922. Divided
and this application filed September 27, 1924. Serial No. 740,846.

The present invention relates to an apparatus for the continuous solidification of hydrocarbon liquids, and is a division of my co-pending application Serial Number 549,141, filed April 3, 1922, and now Patent 1,525,409, Feb. 3, 1925.

The purpose of the present invention is to provide an improved apparatus wherein hydrocarbon liquids and an emulsifying substance may be continuously fed thereto and properly commingled together, wherein a solid fuel may be ejected therefrom, which will be ready for use when dried.

Other objects of the invention will be in part obvious, and in part pointed out hereinafter.

In order that the invention and its mode of use may be readily understood by persons skilled in the art, I have in the accompanying illustrative drawings, and in the detailed following description based thereupon, set out one embodiment of the same.

Figure 1 is a diagrammatic general view of the first installation for the continuous treatment of hydrocarbons wherein a certain number of the foregoing principles have been put in practice; and,

Figure 2 is a diagrammatic general view of a similar installation for the continuous treatment of the same.

As shown in Figure 1, 1 indicates an emulsifying receptacle provided with a double envelope 2 which is traversed by a fluid such as tepid water, steam or the like, raised to a suitable temperature for the formation of the given emulsion. The said receptacle contains the elements which serve the double purpose of mixing elements and feeding elements for the raw material, the said elements herein being constituted by the forks 3, 4, revoluble together with the respective shafts 5, 6, through the intermediary of the gear wheels 7, 8, respectively, engaging a common gear wheel 9 which is actuated by the pinion 10 with the required power. The forks 3, 4 are so disposed that the paths of the mixing arms shall be caused to intersect. The hydrocarbons to be solidified, such as crude petroleum or petroleum residues, enter through a worm tube 11 provided with a feeding cock 12 which is connected through a suitable packing member with the revoluble shaft 5, the latter having formed therein the duct 13 ending at 14 at

different heights upon the mixing arms 3 and within the mass of hydrocarbons already emulsified.

The substance serving to produce the emulsion, for example, a liquid glue, is caused to enter through a worm tube 15 ending in 69 a feeding cock 16 connected with the duct 17 of the shaft 6, the said duct opening laterally at 18 into the receptacle 1. The two worm tubes 11 and 15 are heated by any suitable means, for example, a liquid bath 19 whereby 68 they are brought to the most favorable temperature for forming the emulsion. The fresh petroleum which is thus caused to follow the path of the mixing elements is therefore introduced at once into the already 70 emulsified mass contained in the receptacle 1, is intimately mixed with the said mass and is, so to speak, instantly emulsified.

The fresh glue which is fed in through the duct 17 and the orifices 18 is also immediately stirred up with the already 71 emulsified mass in order to maintain the constant proportions of the constituents entering into the emulsion. Other mixing elements 20, 21, similar to the preceding 3, 4, 80 may be disposed below the latter in order to completely finish the emulsion before discharging the mass from the receptacle 1 through the orifice 22. The evacuation of the emulsified products into the said 85 receptacle is controlled by means of a valve 23.

The emulsified products are caused to pass through a chamber 24 containing a screw conveyor device 25 and are fed into a second receptacle 26 wherein they are mixed 90 with the hardening product, for example, formaldehyde. This second receptacle is similar to the receptacle 1, and is provided with mixing elements 27, 28, mounted respectively on the shafts 29, 30 which are actuated by a set of gearing 31, 32, 33, whereof the driving pinion 34 also serves to actuate the driving gear wheel 35 of the screw conveyor 25.

The hardening product, formaldehyde for 100 example, enters the receptacle 26 through the medium of a tube 36 provided with a feeding cock 37 which is connected through an adequate packing member with the shaft 30 having formed therein a duct 38 connected 105 with different small ducts 39 opening at different heights along the mixing arms 28. The treated products are brought in an auto-

matic manner by their own weight and by reason of the inclined bottom of the receptacle to the orifice 40 provided with the valve 41 opening into the chamber 42 which 5 contains a screw conveyor and discharge device 43 leading to an orifice 44 for the supply of the molding apparatus. In the present case, the said apparatus comprises a conveyor chain 45 whereof each link carries a mold, 10 the consistent mass which is obtained, being caused to fall upon or to be forced into the said molds. To this effect, the chain is actuated by a suitable mechanism.

The blocks or bricks 46 which are thus 15 obtained and are emptied out in an automatic manner by the said chain may be received upon a continuous belt conveyor 47 serving to transport the same to suitable drying places, either in free air or of the 20 heated type, wherein the hardening takes place.

Figure 2 represents a similar form of the installation in Figure 1. In this case, the 25 formation of the petroleum emulsion and the mixing of the same with the hardening substance are effected in a single receptacle, and on the other hand, the products resulting from this treatment are mixed in a second receptacle with a suitable fuel in the 30 powdered state or broken into small fragments. The numeral 48 designates the treating receptacle which is provided with a double envelope 49 containing a fluid such as tepid water or steam at a suitable temperature. 35 The said receptacle has disposed therein the emulsifying elements 50, 51 which are herein constituted by forks revoluble together with the shafts thereof 52, 53 and so disposed as to provide 40 for the intersection of their paths of movement. The said elements are actuated respectively by the gear wheels 54, 55, engaging a common pinion 56 which is actuated from a suitable source of power by means 45 of the gear 57. The emulsifying arms 50 herein serve the double purpose of mixing elements and of elements for feeding the raw material, and to this effect, suitable ducts are formed in the said upwardly extending arms and are caused to open at 58 at the upper part thereof, being connected by a duct 59 with a feeding cock 60 which is 50 adapted to receive from a worm 61 disposed in the bath 62 at constant temperature, on the one hand the hydrocarbon supplied 55 through the piping 63, and on the other hand, the emulsifying substance supplied through the second piping 64; the cocks 65 and 66 serving to regulate the respective supply afforded by the said piping in each case. The mixture of hydrocarbons and emulsifying substance is fed out by overflow from 60 the orifices 58 and is distributed throughout the already emulsified mass 67 whereby the 65 emulsion can be formed in an extremely

rapid manner. The emulsified mass will then descend gradually in the receptacle 48 and will reach the level of the mixing elements 68, 69 which are respectively mounted upon the shafts 52, 53, the paths of movement of the same being also caused to intersect. The mixing elements 69 have formed at the lower ends thereof the orifices 70 which are connected through a duct 71 and a cock 72 with the supply piping 73 for the 75 hardening substance, which latter is thereby instantly distributed throughout the emulsified mass, and the latter is then discharged through the orifice 74.

A valve 75 serves to regulate the discharge 80 of the product through the chamber 76 containing a screw conveyor device 77. In the present case, the said chamber is surrounded by a double envelope 78 which is maintained at a suitable temperature. On the 85 axis of the conveyor 77 is disposed a feeding device 79 mounted below the hopper 80 which contains powdered or broken fuel, whereby the feeding in adequate proportions into the receptacle 81 shall be carried out both for the hydrocarbon which is now in a 90 consistent state and ready to be solidified by cooling and drying, and for the said fuel which is to be agglomerated. The receptacle 81 is provided (as for the receptacle 48) 95 with a double envelope maintained at constant temperature, in all cases where this may be required.

The mixing of the hydrocarbon and the 100 said fuel is effected by means of the mixing elements 82, 83, mounted respectively on the shafts 84, 85, which latter are actuated by a set of gearing 86, 87, 88, 89, as in the preceding case; the pinion 89 actuates by means of the pinion 90 the screw conveyor 77 and 105 the feeding device 79, the said pinion being preferably driven in synchronism with the pinion 56. The products which are emulsified in the receptacle 81 are discharged 110 through the orifice 91, whose section is regulated by the valve 92, and are caused to travel through the chamber 93 containing the screw conveyor device 94, wherefrom they are delivered into the spout 95 for supplying the molds, die plates or presses which 115 serve to produce the suitable shapes for the drying and hardening.

Should the hydrocarbons be mixed with a pulverized solid fuel, the hardening substance may be incorporated with the mass exclusively in the presence of the said fuel, that is to say, in the receptacle 81.

Manifestly, the construction herein shown is capable of considerable modification, and such modification as is within the scope of my claims, I consider within the spirit of my invention.

I claim:

1. An apparatus for the continuous solidification of hydrocarbon liquids comprising 130

a receptacle wherein suitable mixing arms mounted upon a vertical shaft are provided with conduits for the admission of hydrocarbon liquid and of an emulsifier, whilst other mixing arms mounted upon another vertical shaft are provided with conduits admitting the hardening substance into the emulsified mass.

2. An apparatus for the continuous solidification of hydrocarbon liquids comprising a receptacle wherein suitable mixing arms mounted upon a vertical shaft are provided

with conduits for the admission of hydrocarbon liquid and of an emulsifier, whilst other mixing arms mounted upon another vertical shaft are provided with conduits admitting the hardening substance into the emulsified mass, and a cover for said receptacle to which are suspended the mixing elements which are adapted to be lifted together with the said cover.

In witness whereof I have hereunto set my hand.

HIPPOLYTE NEVEU.
